UNITED STATES PATENT OFFICE.

SIMON W. WARDWELL, OF PROVIDENCE, RHODE ISLAND, ASSIGNOR TO WARDWELL BRAIDING MACHINE COMPANY, OF PORTLAND, MAINE, A CORPORATION OF MAINE.

SUPPLY-CARRIER FOR BRAIDING OR OTHER TEXTILE MACHINES.

1,265,146.

Specification of Letters Patent.

Patented May 7, 1918.

Application filed November 21, 1913. Serial No. 802,274.

To all whom it may concern:

Be it known that I, SIMON W. WARDWELL, a citizen of the United States, residing at Providence, in the county of Providence and 5 State of Rhode Island, have invented certain new and useful Improvements in Supply-Carriers for Braiding or other Textile Machines, of which the following is a specification.

10 My invention relates to supply-carriers for braiding or other textile-machines and consists of improvements in the tension-controlling devices therefor. The object of my improvement is to provide a simple and efficient device for controlling the delivery of 15 the yarn or thread from a rotating supply-cop or spool, with means for easy and convenient adjustment of the amount of tension applied to the yarn.

20 The invention is fully set forth in the following specification, illustrated by the accompanying drawings, in which like letters of reference designate like parts.

In the drawings:—

25 Figure 1 is a side elevation of my improved supply-carrier showing the arrangement of the tension-controlling device employed in connection therewith:

Fig. 2 is a plan view of the same;

30 Fig. 3 is an enlarged, detail view of the tension-device;

Fig. 4 is an enlarged, plan view of the same, part sectional on the line X—X of Fig. 3;

35 Figs. 5 and 6 are enlarged, detail views of parts of the adjusting-mechanism for the tension-device.

Referring to Figs. 1 and 2, B designates a usual form of supply-carrier for braiding machines of the rotary type, such, for instance, as that shown in my United States Patent No. 1,032,870, but it will be understood that my improvements are adaptable to different styles of yarn-carriers and for 45 other purposes. The carrier here shown consists of a main deck-portion b, of lenticular outline, formed with a depending runner or shoe b' adapted to slide in the circular track of the braiding machine. Fixedly secured in 50 a boss b² on the deck b is a vertical spindle C on which is rotatably mounted the cop- or bobbin-holder C'. This latter consists essentially of a flanged brake-disk or wheel c and means integral therewith for securing the 55 cop in relation thereto. The holding-means

for the cop may be of any suitable form, but as here shown it comprises the contractible-sleeve c' secured rotatively with the brake-wheel c and provided with spurs or other projections c², c² adapted to indent the interior of the cop-tube z. In Fig. 1 the cop-tube z is represented by dash-lines and its surrounding yarn-mass, which constitutes the cop or other thread-package, as indicated in outline by the dot-and-dash lines Y. 60 The cop-tube z is slipped on over the sleeve c' of the holder C' and the cop is thus secured rotatively with the brake-wheel c so that the two will turn together. Usually a cap or head D is applied to the upper end 70 of the cop Y to provide a smooth rim across which the yarns from the oppositely moving supplies in the braiding machine draw. As here illustrated the cap D consists simply of a circular disk having its rim formed over 75 in the curved flange d and provided with suitable prongs d', d' on its under side adapted to be inserted in the end of the tube z. Extending upwardly from the deck b of the carrier B is a fixed guide or spindle E 80 around which the yarn y from the cop Y leads before it passes to the tension-controlling device which is mounted at the opposite end of the carrier B.

The tension-device is arranged to control 85 the rotation of the supply-cop Y, and thereby the delivery of the yarn y, through coöperation of the yarn-controlled elements with the brake-wheel c. The mechanism of the tension-device is mounted on an upright 90 standard or post F which is preferably constructed from sheet-metal and formed with a foot f secured to the deck of the carrier by suitable means, such, for instance, as the screw f'. At its upper end the member F 95 is bent outwardly and formed with a guide-eye f² through which the yarn y is adapted to lead on its course both to and from the tension-controlling lever G. The controlling-lever G is formed with a tail-piece g having a curved end g' under which the yarn y draws and at its opposite end are two downwardly bent lugs or hinge-members g², g². The lugs g², g² are formed with holes g³, g³ adapted to receive a wire pin H which 100 extends through two laterally extending lugs f³, f³, adjacent the foot of the post F. The lever G also has a curved arm g⁴ which co-operates with a sliding drop-wire I, but this latter arrangement is not herein described in 110

detail as it forms no part of the present invention.

The wire pin H also serves as a pivot for the brake-lever J which engages the flanged 5 rim c³ of the brake-wheel c. As shown more particularly in Fig. 4, the lever J takes the form of a fork having a cross-bar j and two side-members or arms j', j' adapted to straddle the outside of the two lugs f³, f⁴ on 10 the post F, the arms being provided with holes j², j² for receiving the pin H. The pin H is formed with a hooked extension h terminating in the downwardly-bent portion h' which is adapted to enter a depression f⁴ 15 in the foot of the post F. The hook-portion h serves as a spring, so that after the pin H is inserted through the levers G and J and the lugs f³, f⁴, its ends h' can be snapped into the depression f⁴ to hold the pin in 20 place, see Fig. 3.

Referring to Figs. 3 and 4, one of the side-members or arms j' of the lever J is formed with an upwardly-extending, curved finger j³ arranged to overlap a laterally-extending lug or projection g⁵ on the side 25 of the tension-controlling lever G. Extending downwardly from the cross-bar j of the lever J is an elbow-shaped arm j' having its outer face j⁵ adapted to bear against the 30 periphery of the rim c³ of the brake-wheel c. The lever J is caused to bear against the brake-wheel c through the means of a spring K which is fastened to the post F by an adjustable device L whereby its tension 35 can be regulated as required. One end of the spring K is hooked through a hole j⁶ in the cross-bar j of the lever J and its opposite end is hooked around the center of the adjusting-member L which is secured to 40 the post F as next described.

Referring to Figs. 4 and 5, the post F is constructed with a central opening f⁵ extending throughout the greater portion of its length and formed with the parallel 45 sides f⁶, f⁷. Adjacent the upper end of the side f⁷ are a series of notches forming the ratchet teeth f⁸, f⁸, etc. As illustrated more particularly in Fig. 6, the adjusting-member L is formed with openings or slots 50 l, l' at its opposite ends adapted to receive the sides of the opening f⁵ of the post F. The inner end of the slot l is beveled off at l², see Figs. 5 and 6, to adapt it to fit the teeth f⁸ on the post F and the metal punched 55 out from the other slot l' is formed up in a finger l³ adapted to engage the edge f⁹ of the opening f⁵ in the post. The teeth f⁸ act to hold one end of the member L from sliding down on the post F and the finger 60 l³ prevents movement at its other end under the tension of the spring K. To adjust the tension of the spring K it is only necessary to tilt the member L upwardly at the right-hand end and it can then be moved up or 65 down in the opening f⁵ to bring it into en-

gagement with any one of the teeth f⁸. In this way the spring K can be stretched or contracted accordingly as more or less pressure is required between the brake-lever and wheel. The operation of the whole device is as follows:

The cop or other supply package Y is placed on the holder C' where it is held rotatively with respect to the brake-wheel c by means of the sleeve c' engaging the interior of the cop-tube z. The yarn y is led around the guide-spindle E; thence through the guide-eye f² on the post F; down under the curved end g' of the lever G; and back again through the guide-eye f² from which it delivers to the merging point of the other yarns used in the braiding machine. The spring K is adjusted to give the proper amount of tension to press the brake-lever J against the rim c³ of the brake-wheel c and in this way the rotation of the cop-holder is resisted so that tension is applied to the yarn y as it draws from the cop Y. The amount of tension thus applied to the yarn is regulated in accordance with requirements as to the character of the braiding or other operation being performed by varying the tension of the spring K. This adjustment in the tension of the spring is accomplished easily and quickly 95 by merely shifting the fastening-device L up and down on the post F as before described. As the yarn y draws down around the lever G the latter will be lifted to bring it into contact with the finger j³ on the 100 brake-lever J. The pressure of the lever G against the lever J is resisted by the action of the spring K and the tension of the spring is adjusted to such a degree that a relatively slight but constant friction is exerted between the brake-lever J and the brake-wheel c. In this manner the resistance to the rotation of the cop is controlled very sensitively in accordance with the setting of the spring K and a smooth, even 110 tension is thereby maintained on the yarn throughout its delivery from the supply-cop.

I have found by experiment that with my new device the tension on the yarn can be 115 adjusted to an exceedingly minute degree and when the device is once set the tension remains constant and uniform during the continuous draft on the material. The frictional pressure of the brake-lever on the 120 brake-wheel is applied with a velvety smoothness which has never before been approached in devices of this sort and, furthermore, my improved construction and arrangement of the mechanism lends itself to 125 easy and economical manufacture. It has been determined that the brake-wheel c does not need to be made with extreme accuracy and precision, for even if its flange or rim is not exactly true and concentric with 130

its axis, any slight irregularities will be compensated for by the floating movement of the brake-lever. It will be noted that the controlling-spring K for the brake-lever 5 is relatively long so that slight fluctuations in the position of the brake-lever J will not affect its normal tension and, therefore, the lever can adjust itself to any eccentricity in the periphery of the brake-wheel without 10 altering the effect of its pressure thereon. It is also called to attention that practically all of the operating parts of my new device are constructed from sheet-metal so that 15 while being relatively strong and stanch they may be of minimum weight. This feature is especially important in rendering the whole carrier extremely light, so as to adapt it for rapid movement in high-speed braiding machines of the type hereinbefore 20 specified. In addition, the whole device is so ingeniously arranged as to be extremely simple, with the number of parts reduced to a minimum. Both the brake-lever and 25 yarn-lever are pivoted on the same pin, and this is secured in place without screws, nuts or other similar means.

Various modifications might be made in the form and structure of the parts of my new device without departing from the 30 spirit or scope of the invention; therefore, without limiting myself to the exact construction shown and described, what I claim is:—

1. In a yarn-delivering means for braiding or other textile machines, the combination with a supply-carrier having a relatively flat deck with a runner depending from its underside, of a spindle projecting upwardly from the deck of the carrier, a 35 rotatable cop-holder journaled on said spindle, a brake-wheel secured to the lower end of the cop-holder in parallel relation with the deck of the carrier and in close proximity thereto, a friction brake-lever pivoted above 40 the brake wheel to adapt it to bear against the rim thereof, a spring for operating said lever to hold it against the brake-wheel, and a yarn-controlled lever normally maintained out of contact with the brake-lever and 45 arranged to be operated by the pull of the yarn delivering from the cop to cause it to act against the brake-lever to relieve the pressure of the latter on the brake-wheel.

2. In a supply carrier for braiding or 50 other machines, the combination with a rotatable cop-holder having a brake-wheel rotatable therewith, of a friction brake-lever pivoted on the carrier to adapt it to bear against the periphery of the brake- 55 wheel to apply resistance to its rotation, a spring secured at one end to the brake-lever,

means for fastening the opposite end of the spring at a plurality of different points at varying distances from the brake-lever, and a yarn-controlled lever pivoted to swing 60 into contact with the brake-lever but normally held away therefrom solely through the action of gravity whereby a slight pull on the yarn will cause it to bear against the brake-lever and an increase in the tension 70 on the yarn will cause it to act on the brake-lever to relieve the pressure of the latter on the brake-wheel.

3. In a supply-carrier for braiding- or other textile-machines, the combination with 75 a rotatable cop-holder formed with a brake-wheel rotatable therewith, of a standard arranged adjacent thereto and formed with spaced notches, a brake-lever pivoted on the standard and arranged to bear against the 80 periphery of the brake-wheel, a spring having one end secured to the brake-lever, a member secured to the opposite end of the spring and adapted to be adjusted up and down on the notches of the standard to regulate the tension of the spring, and a yarn-controlled lever pivoted on the standard to oscillate independently of the brake-lever but adapted to contact therewith to regulate the braking action on the brake-wheel. 85

4. In a supply-carrier for braiding- or other textile-machines, the combination with 90 a rotatable cop-holder having a brake-wheel, of a standard arranged adjacent thereto, a brake-lever adapted to bear on the periphery 95 of the brake-wheel, a yarn-controlled lever for operating the brake-lever, and a wire pivot pin extending through bearings in said levers and the standard, said pin formed with one end bent into a hook and having 100 its extremity sprung into a depression on the foot of the standard to hold the pin in place.

5. In a supply-carrier for braiding- or other textile-machines, the combination with 105 a cop-holder having a brake-wheel, of a standard arranged adjacent thereto and formed with an opening having parallel sides with ratchet teeth in one of the sides, a member having slots fitted to the sides of 110 the opening to adapt it to slide on the standard and arranged to engage the teeth thereof to hold it in place, a spring secured at one end to said member, and a brake-lever connected to the spring to be operated therefrom to engage the brake-wheel. 115

In testimony whereof I affix my signature in presence of two witnesses.

SIMON W. WARDWELL.
